UNITED STATES PATENT OFFICE.

REINHOLD KIRCHNER, OF MOBILE, ALABAMA.

BUILDING-PROTECTOR.

1,344,540.

Specification of Letters Patent. Patented June 22, 1920.

Application filed December 10, 1918. Serial No. 266,163.

To all whom it may concern:

Be it known that I, REINHOLD KIRCHNER, a citizen of the United States, residing at Mobile, in the county of Mobile and State 5 of Alabama, have invented new and useful Improvements in Building-Protectors, of which the following is a specification.

This invention relates to building protectors, and is in the nature of a protective 10 closure for the openings in building structures.

The object of the invention is to provide an effective protector for the openings in buildings when subjected to floods, the protecting device being adapted to close such openings in the buildings to any desired height and the structure being capable of being applied to any opening in the building either directly within the opening itself or 20 upon the outside of the building adjacent to such opening.

Another object in view is to provide a protector of the character referred to which is of sectional construction so that it may be 25 readily set up and removed as required.

With the above and other objects in view, the invention consists in the novel construction, combination and arrangement of parts as herein fully described, illustrated and 30 claimed.

In the accompanying drawings:

Figure 1 is an outside elevation of a sufficient portion of a building structure to illustrate the improved protecting device in its 35 applied relation thereto,

Fig. 2 is a horizontal section through the same,

Fig. 3 is a vertical transverse section through the same,

Fig. 4 is a fragmentary vertical cross section showing the means for filling the floor channel iron when the protecting device is not in use,

Fig. 5 is a fragmentary horizontal section showing another form of channel iron applied in another way to the wall of the building structure.

Referring to the drawings, 1 designates the walls or masonry of a building structure. 50 In the preferred embodiment of this invention, and in order to obtain the best practical installation of the protecting device, the walls 1 should be of some such material as concrete in order to render them waterproof.

55 In installing the protective device, a chan-

nel iron 2 is sunk flush in the floor 3 of the building, as shown in Fig. 3 and vertical channel irons 4 are mounted flush in the side walls bounding the opening to be closed and protected against floods. The vertical channel irons are arranged directly opposite each other, as shown in Fig. 2 with their channel sides exposed to receive the edges of the closure hereinafter described, the bottom edge of the closure being adapted to be 60 placed in the channel of the first named channel iron 2 in the floor 3. Where possible it is preferred to arrange the channel irons 2 and 4 as shown in Figs. 2 and 3. Under such arrangement the closure will 65 then be within the outside face wall of the building structure, as shown in Fig. 2. Where, by the presence of doors or other obstructions it is impracticable to place the channel iron 4 as shown in Fig. 2, channel 70 irons 4', as shown in Fig. 5, may be provided, such channel irons being arranged against the outer face of the building walls 1 and each of said channel irons having anchoring means 5 shown as L-shaped in formation 75 and embedded in the walls 1. The anchoring means 5 may be either in the form of a continuous flange extending longitudinally of the channel iron 4' or it may consist of several L-shaped projections or arms extending from said channel iron 4'. Under 80 the arrangement shown in Fig. 5 the floor channel iron will, of course, be arranged in alinement with the vertical channel iron 4' so as to receive the bottom edge of the closure. 85

The closure, in the preferred embodiment thereof, consists of a number of vertical posts 6 having vertically extending grooves 7 in the opposite faces thereof. Detachably connected with said posts are horizontally 90 extending panels 8 having a tongue and groove joint, at 9, with each other. The panels 8 also have at their ends projecting tenons or tongues 10 which are detachably fitted in the grooves 7 of the posts 6, as 95 shown in Fig. 2. The closure is thus of separable and knock-down construction adapting it to be easily assembled and placed in position and removed therefrom when no longer required.

100 The closure is set up with relation to the channel irons as illustrated in Figs. 2 and 3, wherein it will be seen that the bottom and side edges of the closure are received in the channel irons 2 and 4 respectively.

A flexible sheet 11 of fabric such as canvas treated with a waterproofing compound is then applied to one face of the closure above described and preferably to the outside exposed face thereof, as indicated in Fig. 2. The channels in the channel irons are wider than the thickness of the closure in order to enable fastening wedges or wedge-shaped strips 12 to be inserted in said 10 channel irons between the closure and one of the flanges of the channel iron for the purpose of binding the marginal portions of the flexible sheet 11 in place. The wedging strips 12 are preferably formed of wood and 15 preferably poplar which will expand readily and quickly when subjected to the action of moisture or water enabling them to more effectively hold the flexible sheet in place, thereby preventing water from reaching the closure proper and warping the same. 20

In applying the flexible sheet 11 to the closure structure a certain amount of slack is left in said flexible sheet so as to enable the wedging strips 12 to be driven into place without tearing or injuring said sheet. As 25 soon as the wooden strips 12 are subjected to the action of the water coming in contact therewith they expand and firmly wedge themselves in place and thereby securely hold the flexible waterproof sheet 11 in place. When the protector is not in use, the channel of the channel iron 2 is filled with 30 an iron filler 13, as shown in Fig. 4, the same being held in place by screws 14, preferably 35 of brass, which will not corrode. The filler 13 may be made in one strip or of several pieces and any desired number of screws 14 may be used to hold the filler in place. This 40 leaves a flush floor surface when the protective device is not in use.

The upper marginal portion of the flexible sheet 11 may be placed over the top edge of the closure and tacked or otherwise fastened thereto. Braces 15 may also be placed 45 behind the posts 6 of the closure to withstand the action of rushing water when a flood is rising rapidly. The height of the complete closure may be determined by reference to previous flood conditions.

50 I do not desire to be limited to the exact

construction herein shown and described, it being apparent that the invention is susceptible of many changes in the form, proportion and minor details of construction which may accordingly be resorted to without departing from the principles or sacrificing any of the advantages of the invention. 55

Having thus described the invention, 60 what I claim is:

1. In a protective closure for building structures, the combination of channel irons having a permanent anchored connection with the walls bounding an opening in such structure, a closure adapted to have the edges thereof seated in the channels of said channel irons, a sheet of waterproof fabric covering the face of said closure, and separable fastening means adapted to be inserted in said channel irons for holding the marginal portions of said sheet in place. 70

2. In a protective closure for building structures, the combination of channel irons having a permanent anchored connection 75 with the walls bounding an opening in such structure, a closure adapted to have the edges thereof seated in the channels of said channel irons, a sheet of waterproof fabric covering the face of said closure, and fastening means applicable to marginal portions of said sheet and channel irons to fasten said sheet in place, said closure being composed of spaced posts and panels of different widths having a tongue and groove 80 jointed connection with each other. 85

3. In a protective closure for building structures, the combination of channel irons having a permanent anchored connection with the walls bounding an opening in such 90 structure, a closure adapted to have the edges thereof seated in the channels of said channel irons, a sheet of waterproof fabric covering the face of said closure, and fastening wedges expansible by moisture applicable to marginal portions of said sheet and channel irons to fasten said sheet in place. 95

In testimony whereof I affix my signature.

REINHOLD KIRCHNER.
